Designer Appliances <https://www.designerappliances.com/lgw-m3600hwa-dlg3601w-kstk1.html> (Year: 2021).*Primary Examiner — Michelle E. Wilson*Assistant Examiner* — Richard E Yenchesky(74) *Attorney, Agent, or Firm* — Birch, Stewart, Kolasch & Birch, LLP(57) **CLAIM**

The ornamental design for an electronic washing and drying machine for laundry purpose, as shown and described.

DESCRIPTION

FIG. 1 is a front perspective view of the electronic washing and drying machine for laundry purpose showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view, with the control panel shown in use.

The broken lines depict portions of the electronic washing and drying machine for laundry purpose that form no part of the claimed design.

1 Claim, 8 Drawing Sheets(56)
